George Dryden

GEORGE DRYDEN, OF WORCESTER, MASSACHUSETTS, ASSIGNOR
TO R. BALL AND COMPANY, OF SAME PLACE.

Letters Patent No. 89,207, dated April 20, 1869.

IMPROVEMENT IN WOOD-WORKING MACHINES.

The Schedule referred to in these Letters Patent and making part of the same.

Know all men by these presents:

That I, GEORGE DRYDEN, of the city and county of Worcester, and Commonwealth of Massachusetts, have invented certain new and useful Improvements in Wood-Working Machines; and I do hereby declare that the following is a full, clear, and exact description of the same, reference being had to the accompanying drawings, forming part of this specification, in which—

Figure 1 represents an end view of so much of a wood-working machine as is necessary to illustrate my invention;

Figure 2 represents a central section of the same, at line A B, fig. 1; and

Figure 3 represents a plan view of the journal-box, with the cutter-head removed.

To enable those skilled in the art to which my invention belongs, to make and use the same, I will proceed to describe it more in detail.

The nature of my invention consists—

First, in the combination, with the spindle to which the cutter-head is attached in matching and other wood-working machines of a hollow spindle and pulley, cast in one piece, as hereinafter explained.

Second, in the combination, with the cutter-head in a matching, or other wood-working machine, of a bisected spindle, the parts of which are constructed and combined together in the peculiar manner shown and hereafter described.

Third, in the combination, with the frame which supports the matcher-head spindle, of an oil-chamber and cap, as hereafter described.

In the drawings—

The part indicated by letter A is the main frame of the machine, constructed in the usual manner.

To the cross-piece B is attached a frame, C, having a journal-box, D, and a step-bearing, E, in which are supported and turn the hollow spindle F and pulley G.

The pulley G and spindle F are cast in one piece, and cored out hollow, the pulley as indicated by red lines, fig. 2.

The cutter-head H is secured, by a set-screw, a, to the top end of a bisected spindle, L M, which passes through the hollow spindle F and pulley G, with its lower end resting on the step E.

The top part L of the bisected spindle is turned with a tapering stem N, which fits into a corresponding shaped hole in the lower part M, where it is secured by a set-screw, b, which screw also secures the bisected spindle in the hollow spindle F.

An opening, c, is formed through the part M in which to insert a lever for starting out the stem N.

The extreme end, m, of the stem N, that extends into the slot, or opening c, is made flat to fit the same,

thus preventing the parts M and L from turning separately.

The cutter-head may be adjusted at different heights by the screw d in its top.

A semicircular groove, f, is formed in the top of the journal-box D, or frame C, from which holes communicate with the bearing part which supports the upper part F of the hollow spindle.

The groove f is to be filled with cotton-waste and oil, the latter being gradually drawn, or conveyed to the bearing, for lubricating the same.

A sliding cover, K, is arranged above the groove f, to protect and shield the waste and oil from chips and dust.

The sliding cover is retained in place by a set-screw, t.

In using machines simply for surface-planing, it is sometimes desirable to remove the matchers, or vertical cutter-heads, and the object of my invention is to furnish a device by which it can be done in a more convenient manner than heretofore:

To remove the cutter-head, the set-screw b is loosened, when the cutter-head H and spindle L M can be lifted out, while the pulley G and hollow spindle F still remain in position.

The cover K is moved over the opening in the spindle F, thereby preventing chips and dirt from falling in.

The spindle L M may be made whole, that is, in one piece, if preferred, when the combined hollow spindle F and pulley G are used, and I propose to adopt such construction in the manufacture of new machines, but in machines already built, I shall use the bisected spindle L M, the lower end of which is made flat, as shown at m, in which case the cutter-head would be removed, by simply removing the part L.

The driving-pulley being attached, in this instance, to the part M, will remain in proper position to support the belt, the same as in the former case.

By casting the spindle F and pulley G in a single piece, and coring out such parts for the reception of the removable spindle, the manufacture of the machine is greatly facilitated, while, at the same time, it is rendered more durable.

Then, again, by the use of the cast-iron spindle F, the cutter-head has less vibration than in the old machines, thereby producing better work.

The flattened end m of the part L, fitting, as it does, closely into the slot c, in the part M, obviates an objection to the use of spindles with screws on their lower ends, which are liable to unscrew when the heads are turned back for any purpose.

Having described my improvements in wood-working machines,

What I claim therein as new, and of my invention, and desire to secure by Letters Patent, is—

1. The upper part L and lower part M of the divided spindle, and the set-screw b, when said parts are constructed and arranged for joint operation, as shown and described.

2. The hollow spindle F and pulley G, formed, or cast in one piece, in combination with the spindle L

M, said parts being constructed substantially as shown and described.

3. The combination with the frame C, or journal-box D of the oil-chamber, with its sliding cap K, substantially as and for the purposes set forth.

Witnesses:

THOS. H. DODGE,
GEO. H. MILLER.

GEORGE DRYDEN.
